UNITED STATES PATENT OFFICE.

JOSÉ IBARRA, OF HABANA, CUBA.

CIGARETTE-BOX-GROUPING MACHINE.

1,143,400.

Specification of Letters Patent. Patented June 15, 1915.

Application filed April 28, 1914. Serial No. 834,951.

To all whom it may concern:

Be it known that I, JOSÉ IBARRA, a citizen of Cuba, and a resident of Habana, Cuba, have invented a new and Improved Cigarette-Box-Grouping Machine, of which the following is a full, clear, and exact description.

Among the principal objects which the present invention has in view are: to provide means for arranging in convenient order cigarette boxes so that the same may be formed into what is termed a "wheel"; to provide means for grouping said boxes and coincidentally fixing the ends of the sealing stamps with which said boxes are provided; and to provide a simple, efficient and accurate mechanism for accomplishing the objects stated.

Drawings.—Figure 1 is a plan view of a mechanism of a machine constructed and arranged in accordance with the present invention, the same being shown in conjunction with a fragment of the conveyer bench of a cigarette-box stamp-applying machine; Fig. 2 is a side elevation of the same; Fig. 3 is an end elevation of the same.

Description.—As shown in the accompanying drawings, the bench 8 is hollowed, or box-like in form to provide passages for the delivery of cigarette boxes, such as indicated by the numerals 9 in Figs. 1 and 2 of the drawings. To support the present machine in working relation to said bench, a vertically-disposed bolting flange 10 is mounted on said bench. The flange 10 is slotted to form a guide for a plunger 11. The plunger 11 is reciprocated by any conventional and suitable mechanism, said mechanism being preferably connected with the mechanism by which the boxes 9 are advanced through the passages in the bench 8.

The present machine is formed as a chute, having a delivery floor 12 and a partial deck 13. The deck 13 is supported on guide rails 14 and a central partition 15. The partition 15 is alined with the partition 16 in the bench 8, which partition divides the passageway for the boxes 9. The deck 13 has a plurality of openings formed therein and extending therethrough. In the present disclosure, two such openings are formed, each being disposed in line with the ends of revenue stamps 17, which are applied to the boxes 9 by a suitable machine, the ends of said stamps being left by said machine in a

slightly loosened condition. These ends are pressed solidly upon the boxes to aid in fixing said ends by being pressed upon by the rollers 18, to receive which, the recesses 60 above mentioned are formed in the deck 13. The rollers 18 above referred to are united by a shaft 19, on which presses a flat spring 20. The spring 20 is structurally mounted on the deck 13 by a pin or rivet 21. The 65 spring 20 operates to press upon the shaft 19 to normally hold the rollers 18 so that the lower edge thereof extends below the under surface of the deck 13 and in the path of the boxes 9. The boxes 9, in passing, 70 engage and lift the rollers 18 from their seats in the deck 13, the spring 20 yielding to permit this action. The delivery floor 12 is held flush with the floor of the bench 8 by brackets 22, through which bolts 23 pass. 75 The brackets 22 are bolted to the flange 10, through an opening in which extends the plunger 11. The plunger 11 is reciprocated by any suitable means, the object of this movement being to permit a latch head 24 to 80 engage the pendent arm 25 of an elevator 26. The latch head 24 is formed at the end of a rocking lever 27, to the long end whereof is attached a spring 28. The spring 28 is entered at the far side of the plunger 11, 85 and draws the long end of the lever 27 against the stop block 29. The stop block 29 limits the movement of the lever 27.

The above-described construction permits the lever 27 to freely rock on the pivot 30, 90 to permit the head 24 to yield when striking the arm 25 in the outward movement of the plunger 11, and to assume an engaging position beyond the end of the arm 25.

The elevator 26 is pivotally mounted on a 95 shaft 31, and is bifurcated or provided with a double-extension platform, as seen best in Fig. 1 of the drawings. Extending upwardly from the hub or bearing 32 to which the platform is attached is an arm provided 100 to engage a pull-spring 33. The opposite end of the spring 33 is secured to an eyelet 34 at the side of the machine. The platform of the elevator 26 is normally held by the spring 23 in flush arrangement with the delivery floor 12 of the machine. 105

Operation.—In a machine constructed as above described, and as shown in the accompanying drawings, the operation is as follows:—By a suitable intermediate feed 110 mechanism, the boxes 9 are delivered through the bench 8 upon the floor 12 of

the present machine. As before stated, the stamps 17 have been applied to the boxes in a manner which disposes the free ends thereof at the top of the boxes and in the path 5 of the rollers 18. In the process of advancing the boxes to the elevator 26, said stamps pass under and are pressed upon by the rollers 18, the pressure applied being exerted by the spring 20. One of the intermittent 10 movements feeding the boxes 9 places the end box fairly upon the elevator 26, one box of each of the two rows shown passing over one of the sections of said elevators.

15 Simultaneous with the retractive movement of the intermittent advancing mechanism, the plunger 11 is drawn inward or toward the flange 10. The head 24 extends into the path of the arm 25 and engages the same to swing the elevator 26 to a vertical 20 position, the head 24 passing under and beyond the arm 25. In this position of the elevator 26, the box 9 is lifted to rest upon its edge, and the elevator 26 is returned by the spring 33 to the normal position thereof, 25 flush with the delivery floor 12, and ready to receive the next succeeding box 9 when delivered thereto.

Claims:

1. A cigarette box grouping machine, 30 comprising a delivery floor; a partition dividing the same lengthwise; an elevator having a plurality of wing-like members disposed normally flush with said floor;

Copies of this patent may be obtained for five cents each, by addressing the "Commissioner of Patents, Washington, D. C."

means pivoting said elevator at the outer end thereof; an actuating arm for said elevator extending below said floor; a reciprocating plunger; a latch head mounted on said plunger; means for rigidly holding said latch head in the path of said arm to engage the same when traveling in one direction only, and yielding means for moving said latch to normally engage said rigid means.

2. A cigarette box grouping machine, 35 comprising a delivery floor; a partition dividing the same lengthwise; an elevator having a plurality of wing-like members disposed normally flush with said floor; means pivoting said elevator at the outer end thereof; an actuating arm for said elevator extending below said floor; a reciprocating plunger; a latch head mounted on said plunger; means holding said latch head in the path of said arm to engage the same when traveling in one direction only; and 40 automatic means for returning said elevator to its normal position when not engaged by said latch head.

In testimony whereof I have signed my name to this specification in the presence 45 of two subscribing witnesses.

JOSE IBARRA.
